CLAIM

The ornamental design for a wireless remote control, as shown and described.

DESCRIPTION

FIG. 1.1 is a front perspective view of a first embodiment of a wireless remote control showing our new design;

FIG. 1.2 is a rear perspective view of FIG. 1.1;

FIG. 1.3 is a front view of FIG. 1.1;

FIG. 1.4 is a top view of FIG. 1.1;

FIG. 1.5 is a bottom view of FIG. 1.1;

FIG. 1.6 is a rear view of FIG. 1.1;

FIG. 1.7 is a right view of FIG. 1.1;

FIG. 1.8 is a left view of FIG. 1.1;

FIG. 2.1 is a front perspective view of a second embodiment of the wireless remote control showing our new design;

FIG. 2.2 is a rear perspective view of FIG. 2.1;

FIG. 2.3 is a front view of FIG. 2.1;

FIG. 2.4 is a top view of FIG. 2.1;

FIG. 2.5 is a bottom view of FIG. 2.1;

FIG. 2.6 is a rear view of FIG. 2.1;

FIG. 2.7 is a right view of FIG. 2.1;

FIG. 2.8 is a left view of FIG. 2.1;

FIG. 4.1 is a front perspective view of a fourth embodiment of the wireless remote control showing our new design;

FIG. 4.2 is a rear perspective view of FIG. 4.1;

FIG. 4.3 is a front view of FIG. 4.1;

FIG. 4.4 is a top view of FIG. 4.1;

FIG. 4.5 is a bottom view of FIG. 4.1;

FIG. 4.6 is a rear view of FIG. 4.1;

FIG. 4.7 is a right view of FIG. 4.1;

FIG. 4.8 is a left view of FIG. 4.1;

FIG. 5.1 is a front perspective view of a fifth embodiment of the wireless remote control showing our new design;

(Continued)

FIG. 5.2 is a rear perspective view of FIG. 5.1;
 FIG. 5.3 is a front view of FIG. 5.1;
 FIG. 5.4 is a top view of FIG. 5.1;
 FIG. 5.5 is a bottom view of FIG. 5.1;
 FIG. 5.6 is a rear view of FIG. 5.1;
 FIG. 5.7 is a right view of FIG. 5.1;
 FIG. 5.8 is a left view of FIG. 5.1;
 FIG. 7.1 is a front perspective view of a seventh embodiment of the wireless remote control showing our new design;
 FIG. 7.2 is a front view of FIG. 7.1;
 FIG. 7.3 is a top view of FIG. 7.1;
 FIG. 7.4 is a bottom view of FIG. 7.1;
 FIG. 7.5 is a rear view of FIG. 7.1;
 FIG. 7.6 is a right view of FIG. 7.1;
 FIG. 7.7 is a left view of FIG. 7.1;
 FIG. 8.1 is a front view of an eighth embodiment of the wireless remote control showing our new design;
 FIG. 8.2 is a top view of FIG. 8.1;
 FIG. 8.3 is a bottom view of FIG. 8.1;
 FIG. 8.4 is a rear view of FIG. 8.1;
 FIG. 8.5 is a right view of FIG. 8.1;
 FIG. 8.6 is a left view of FIG. 8.1;
 FIG. 10.1 is a front perspective view of a tenth embodiment of the wireless remote control showing our new design;
 FIG. 10.2 is a front view of FIG. 10.1;
 FIG. 10.3 is a top view of FIG. 10.1;
 FIG. 10.4 is a bottom view of FIG. 10.1;
 FIG. 10.5 is a rear view of FIG. 10.1;
 FIG. 10.6 is a right view of FIG. 10.1;
 FIG. 10.7 is a left view of FIG. 10.1;
 FIG. 11.1 is a front view of an eleventh embodiment of the wireless remote control showing our new design;
 FIG. 11.2 is a top view of FIG. 11.1;
 FIG. 11.3 is a bottom view of FIG. 11.1;

FIG. 11.4 is a rear view of FIG. 11.1;
 FIG. 11.5 is a right view of FIG. 11.1;
